UNITED STATES PATENT OFFICE.

ISAAC E. SHELLEY AND SIMON A. SHELLEY, OF CRAWFORDSVILLE, INDIANA.

MAIL-BAG-HANDLING APPARATUS.

1,136,281.

Specification of Letters Patent. Patented Apr. 20, 1915.

Application filed July 30, 1913. Serial No. 782,031.

To all whom it may concern:

Be it known that we, ISAAC E. SHELLEY and SIMON A. SHELLEY, citizens of the United States, residing at Crawfordsville, in the county of Montgomery and State of Indiana, have invented certain new and useful Improvements in Mail-Bag-Handling Apparatus, of which the following is a specification.

10 Our invention relates to mail bag handling apparatus. The invention aims to provide a novel, practical and efficient device of this kind, particularly improved with respect to means arranged along a railway track for catching a bag carried by the car; with respect to means for supporting said means from a movable carriage; with respect to means for braking the movement of said carriage; 20 with respect to novel means for supporting a bag to be caught by said means, from a car; with respect to means for supporting a bag from said means arranged along a track; with respect to means for catching 25 said bag, the latter means being carried by a car, and with respect to means for supporting said latter bag operable through the catching of the bag to retract or move inwardly parts of the means supporting the 30 same so as to occupy minimum space and not interfere with other parts employed or projecting from the car.

The other advantages and objects of the invention which are mostly minor in nature, will appear hereinafter from the description following, taken in connection with the accompanying drawings which illustrate one embodiment thereof.

In said drawings:—Figure 1 is a view 40 illustrating the various parts in end elevation and in connection with a car, the latter being but partially shown and partly in section; Fig. 2 is a side elevation, partly in section, of the means arranged along the 45 railway track for catching the bags suspended from cars, traveling on the track; Fig. 3 is a top or plan view of the parts shown in Fig. 2.

Throughout the various views of the 50 drawings, like reference characters designate like or similar parts.

Referring to the drawings, the means arranged along the railway track for catching a bag projected from the car is gen-

erally designated A. Before describing this means in detail, it might be well to first describe the means for projecting the bag to be caught by said means, from the car. This means is shown generally at B. In said means B a bag-supporting frame is employed which has horizontal arms 1 spaced apart by a connecting arm 2 having fastened thereto a handle as at 3. The arms 1 are slidably mounted in bearing portions at 4 formed in plates 5 which are fastened together as by means of bolts at 6. These plates 5 form a supporting frame for the bag-supporting frame and are hinged as at 7 to the interior wall of a car which is shown in Fig. 1 and generally designated C. A compression spring 8 is employed and connected to the car and to the frame provided by the plates 5, as seen in Fig. 1. This spring may be arranged so as to normally maintain the arms 1 projected or 60 to maintain the mechanism B as a whole retracted or in longitudinal relation with the side of the car. Preferably the spring is arranged so that the mechanism B will be maintained in retracted position. Thus, 65 when the mechanism B is moved to projected position, as seen in Fig. 1, the same must be positively maintained in such position as through manual engagement at the handle 3. When released by the hand, it is 70 clear that the mechanism B will be turned on its hinges at 7 by the spring 8 and moved 75 inwardly of the car C.

Referring to the mechanism at A, the various parts comprising the same are carried by any suitable support means such as by a plurality of beams 9. To the beams 9 is suitably fastened a longitudinal beam 10, shown in the form of an I-beam whose flanges 11 serve as rails. Adjacent the upper end of the beams 9 is fastened a beam 12 being substantially in the form of the letter C formed by straight lines. This beam 12 has flanges 13 forming rails. Below the beam 12 and fastened thereto is a rail 100 or rails 14 which preferably forms or form part of an L-beam or beams, as shown.

A carriage is employed and its frame essentially consists of a bracket 15 fastened to a platform or plate 16 having fastened thereto a plate 16'. On suitable axles which may be afforded by bolts 17, are mounted rollers 18 having peripheral grooves adapt-

ed to receive the flanges or rails 11, the rollers being adapted to ride on said rails.

Suitably supported from the plate 16 of the carriage, as by means of U-bolts 19 affording bearings, are axles or shafts 20 on which are mounted rollers designated 21. These rollers are provided with grooves in their peripheries and are adapted to travel on the rails 13, and to receive said rails in the grooves thereof. On opposite sides of the rails 13 are mounted from the plate 16' as on bolts 22 affording axles, rollers 23 which are adapted to travel on opposite faces of one of the rails 13. This construction prevents sidewise jolting of the parts when engaging a mail bag, such as would tend to break or chip the flanges provided by the grooving of the several rollers described.

20 On the bracket 15 is slidably mounted a bracket 24 supporting a suitable axle or short shaft on which is mounted a roller 25 adapted to ride or travel on the rails 14 and having a groove which is adapted to receive the said rail. (See Figs. 1 and 2.) The rails 14 are mounted so that they will have an inclined face at 26 in effect forming a cam with which the roller 25 co-operates. Specifically, the rails 14 are shown as mounted on an inclined plane by means of brackets designated 27.

Bracket 25 rests upon or is fastened to a suitable expansive spring device designated 28. The specific form of the spring shown employs a number of laminated blades or leaves, the innermost ones of which are pivoted together as at 29. A projection 30 is formed in the bracket 15 and the lowermost blade of the spring 28 rests thereon or is fastened thereto. A diagonal brace arm designated 31 is fastened to the bracket 15 and to the plate 16.

Suitable blocks or supports 32 are fastened to the underside of the plate 16 and from each block extends outwardly substantially longitudinally of the car, a catcher arm designated 33. Adjacent the catcher arms 33 are mounted second catcher arms 34 on pivots 35. Coil return springs 36 are employed, being fastened to the catcher arms 34 and to eye members 37 fastened to the plate 16. The walls of the blocks 32 which may be designated 38 are straight and the springs 36 tend to normally maintain the arms 34 in engagement with said walls. It will be noticed that the catcher arms 33 and 34 are flared or curved at 39. By reason of this construction, considerable space is provided intermediate the same at their free ends so that they may properly engage a bag at the various lateral positions which a train may assume in travel caused by the rocking thereof. Should the space intermediate the deflected portions 39 prove insufficient, the yieldable arms will be acted

upon by the engaged or caught mail bag, thus shifting the same and permitting the proper engagement with the bag.

The arms 33 and 34 as seen in Fig. 1, are arranged to catch a mail bag supported by the arms 1, which bag may be designated 40. When the bag is engaged by the arms 33 and 34 it will be positively retained thereby in view of the fact that the arms at their portions adjacent the blocks 32 are at a less distance apart than the width or diameter of end pieces 41 employed on the bag 40. When the bag is engaged by the arms 33 and 34, the momentum or impact caused thereby, moves the carriage and causes the rollers 18, 21, 23 and 25 to move on their respective rails. During such movement, the roller 25 will be depressed by its engagement with the cam face 26 of the rails 14 which will compress the spring 28 and cause the same to press the bracket 21 upwardly as far as possible and the roller 25 into tight frictional relation with the cam face. Thus, the movement of the carriage will be braked and checked in a suitable manner after the carriage has caught a bag. The same action of course takes place regardless of which pair of arms 33 and 34 catch the bag, depending of course upon the direction of travel of the car or train.

Suitable means is provided whereby the bag 40 may be removably suspended by the arms 1 in a position to be caught. As shown, clasp devices are employed which may employ a first arm 42 being pivotally fastened as desired at 43 to the arms 1. Arms 42 have pivoted thereto second arms 44 which are normally maintained at their outer ends in contact therewith by means of the springs 45. The bags on opposite ends have eye members or the like at 46 and the free ends of the arms 42 and 44 extend into the eye and engage each other, thereby supporting the bag in the position shown in Fig. 1.

On the carriage is secured suitable means for supporting a mail bag to be caught by suitable means on a train. Such a mail bag is designated 47 and supported from slideable arms 48. On the arms 48 are fastened eye or guide members 49 through which pass flexible trip elements or cords 50 which are in turn fastened (see Fig. 1) in eyes 51 of retainer arms 52, the latter being pendently supported by the elements 50. To the retainer arms 52 are pivoted retainer arms 53 at 54, the straight portions thereof having fastened thereto a compression spring 55 which normally maintains the arms in closed relation. The retaining ends of the arms 52 and 53 are arcuate, as shown, and terminate in lugs 56. Said bag 47 is provided with eye members 58 and into the eyes of which the lugs 56 are adapted to extend as seen in Fig. 1. When the bag 47 is caught by suitable means, later to be described, the eye

member will be moved to separate the lugs and permit the removal of the bag. After such removal, spring 55 immediately restores the retainer members to closed position.

As to means for supporting the slideable arms 48, they are mounted to slide or telescope within casings 59, one being fastened by U-bolts 60 to the plate 16 and the other being fastened by U-shaped bolts 61 to a bracket 62 fastened at 63 to the brace arm 31. Within the casings 59 are compression springs 64 which are fastened to the casings and to the inner ends of the arms 48, tending to normally maintain the latter within the casings. Prior to fastening the bag 47 to the retaining arms 52 and 53, the arms 48 are moved to projected position as seen in Fig. 1 and suitable means is provided for maintaining the arms projected. Such means is best seen in Figs. 1 and 3 and consists of a bracket or plate 65 fastened as by means of U-bolts 66 to each of the casings 59. On a pin 67 fastened to the bracket 65 is mounted a latch 68 having an end adapted to engage in a notch or recess 69 formed in the arm 48. A spring 70 is fastened to the latch and to a suitable lug 71, and normally tends to shift said latch so that it will engage said notch. An opening is provided in the latch 68 and thereat is fastened one end of the flexible trip elements 50, previously referred to.

In the operation of fastening the bag 47, the arms 48 are first pulled outwardly from the casings 59 a sufficient extent so that the springs 70 will force the latches 68, during such movement into engagement with the notches 69, thereby preventing the return of the arms 48 by their springs 59, upon release of the arms. Thereupon, the retaining arms 52 and 53 are moved relatively at their straight or handle portions so as to spread the members apart. Thereupon, they are properly positioned with respect to the eye members 58 and released so that the lugs 56 will extend thereinto and abut, thereby removably fastening the bag. As previously set forth when the bag is removed, the eye members act against the curved walls or faces at 57 and cause the retaining arms 52 and 53 to separate against the tension of the springs 55.

As to the means carried by the car for catching the bag 47, the same is seen in Figs. 1 and 4 and designated generally D. To the car side is fastened a suitable bracket 72 in which is mounted for slideable movement a stem or rod 73 of a catcher frame generally designated 74, the stem being yieldably held in its normal position by any suitable means. The catcher frame is provided with a stop arm or lug 77 which is adapted to engage the car wall at the doorway. On said frame 74 is mounted any

suitable form of catcher hook or arm device 78. When the arm 78 engages a bag, it does so at the middle or reduced portion thereof, that is a bag of the type shown in Fig. 1, and the bag moves on to the frame 78 to 70 the greatest extent possible and then depends equally on opposite sides thereof. The shock incidental to such action is taken up by the means mentioned above and the catcher 76 and the catcher device slides to 75 some extent against the tension of such spring. The movement of the catcher device is limited by the stop member 77.

The general operation of the several mechanisms and parts employed will now be described.

The bags 40 and 47 or their equivalents are supported respectively from the car and from the arms 48 by the retainer arms 42 and 44 and retainer arms 52 and 53. As 85 the train travels by the support arranged along the track, the bag 40 will be engaged by the arms 33 and 34, the impact causing the carriage to travel on the several rails 11, 13, and 14 through the instrumentality 90 of the rollers described. Especially the roller 25 moves in a vertical plane due to its action against the cam face 26 of the rails 14. This roller 25, as previously set forth, moves with its bracket 24 on the bracket 15 95 against the tension of the spring 28. The spring 28 is a very strong spring and the rails 14 are positioned at such an incline that as the carriage moves along the rails supporting the same the roller 25 will be 100 held in very tight engagement with the rails 14 which it engages thus causing the carriage to be brought to a stop before it reaches the ends of the rails. Of course it is understood that the various rails must be 105 of sufficient length to prevent any danger of the carriage being thrown off the ends of the rails. As to the other bag 47, the same is fastened by means of the retainer arms 52 and 53 after the arms 48 have been projected from the casings 59 and locked in projected position by the latches 68. As the train or car travels toward the bag 47, the catcher arm 78 will engage the bag 47 at its 110 central or reduced portion and catch the same as previously described. The shock incidental to this catching of the bag is taken up by the spring 73 which enables the frame 74 to slide a limited extent in the bracket 72. As the bag 47 disengages the retainer arms 115 52 and 53, the eye members act against the curved faces 57.

It is to be noted that we have merely described one embodiment of the invention for the purpose of this application and that such changes as may be made within the spirit and scope thereof, and fall within the spirit and terms of the appended claims are reserved.

Having thus described our said invention,

what we claim as new and desire to secure by Letters Patent is:—

1. In an apparatus of the character described a track comprising an upper rail, a lower rail, intermediate rails positioned between said upper and lower rails and sloping upwardly from the end portion of said track toward the intermediate portion thereof, a frame, rollers carried by said frame and engaging said upper rail, rollers carried by said frame and engaging said lower rails, a support slidably mounted upon said frame, a roller carried by said support, and means yieldably holding said support in a raised position to retain its roller in tight engagement with one of said rails.

2. In a device of the character described a track including upper and lower supporting rails, binding rails positioned between said upper and lower rails and sloping upwardly from the end portion of said track toward the intermediate portion thereof, a frame, supporting wheels carried by said frame and engaging said upper and lower supporting rails, supporting means slidably mounted upon said frame, a roller carried by said supporting means and engaging one of said binding rails, and resilient means carried by said frame and engaging said supporting means to yieldably hold said supporting means in a position to retain its roller in tight engagement with said binding rails.

3. In an apparatus of the character described a track including an inclined rail, a frame slidably mounted upon said track, supporting means slidably carried by said frame, a roller carried by said supporting means and engaging said inclined rail of said track, and means for yieldably holding said supporting means in a position to retain its roller in tight engagement with said inclined rail.

4. In an apparatus of the character described a track including an inclined rail, a frame movably mounted upon said track, said frame being provided with an abutment, supporting means slidably mounted upon said frame and provided with a roller engaging said inclined rail of said track, and resilient means mounted upon the abutment of said frame and engaging said supporting means to yieldably hold the same in

a position to retain its roller in tight engagement with said inclined rail.

5. In an apparatus of the character described a supporting track including a cam element, a frame movably mounted upon said track, supporting means movably mounted upon said frame, and a roller carried by said supporting means and engaging said cam element, and resilient means carried by said frame and engaging said supporting means to yieldably hold the same in a position to retain its roller in tight engagement with said cam element.

6. In an apparatus of the character described a track including a cam element, a frame movably mounted upon said track, supporting means slidably mounted upon said frame, a roller carried by said supporting means and engaging the cam element of said track, and means for yieldably holding said supporting means in a position to retain its roller in tight engagement with said cam element.

7. In an apparatus of the character described a track including an upper rail, a lower rail, and a cam rail positioned between said upper and lower rails, said upper rail constituting a housing having one side wall provided with a longitudinally extending slot and said lower rail being provided with upper and lower bearing surfaces, a frame, rollers carried by said frame and engaging the upper and lower bearing surfaces of said lower rails, an arm extending from said frame into said housing forming said upper rail, rollers carried by said arm and engaging the outer and inner faces of the slotted side wall of the housing, other rollers carried by said arm and engaging the slotted side wall of said housing at the upper and lower edges of the slot formed therein, a binding element slidably connected with said frame and engaging the inclined rail of said track and means for yieldably holding said binding element in tight engagement with said inclined rail.

In testimony whereof we affix our signatures in presence of two witnesses.

ISAAC E. SHELLEY.
SIMON A. SHELLEY.
